CLAIM

The ornamental design for a display screen or portion
thereof with graphical user interface, as shown and
described.

DESCRIPTION

FIG. 1 is a front perspective view of a display screen or
portion thereof with graphical user interface showing my
new design;

FIG. 2 is a front view thereof; and,

FIG. 3 is a right-side view thereof.

(Continued)

The broken lines in the drawings show portions of the display screen or portion thereof and portions of the graphical user interface that form no part of the claimed design.

1 Claim, 3 Drawing Sheets
